(57) CLAIM

The ornamental design for a toy storage basket with play mat, as shown and described.

DESCRIPTION

FIG. 1 is a front perspective view of a toy storage basket with play mat, showing my new design; FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a front perspective view of the toy storage basket with play mat, shown in an alternate configuration in a closed state;

FIG. 10 is an enlarged detail view of area 10 in FIG. 1; and, FIG. 11 is an enlarged detail view of area 11 in FIG. 1.

The broken lines representing stitching form no part of the claimed design.

The dash-dot-dash broken lines encircling the enlarged views are for annotative purposes only and form no part of the claim thereof.

The broken line showing the interior of the article in FIG. 3 depicts portions of the toy storage basket with play mat that form no part of the claimed design.
